UNITED STATES PATENT OFFICE.

ALBERT KRAUTH, OF HAMILTON, OHIO.

PAPER-CUTTER.

1,098,508.

Specification of Letters Patent.

Patented June 2, 1914.

Application filed February 20, 1911. Serial No. 609,743.

To all whom it may concern:

Be it known that I, ALBERT KRAUTH, a citizen of the United States, residing at Hamilton, in the county of Butler and State 5 of Ohio, have invented certain new and useful Improvements in Paper-Cutters, of which the following is a specification.

My invention relates to means for severing a strip of paper into predetermined 10 lengths and compiling the same one above the other.

One of the objects of my invention is to provide means for cutting a strip of paper into predetermined lengths from a continuous 15 roll, fed between combined feeding and serving rolls, one roll journaled yieldingly relative to its companion roll and against which it engages, together with means for releasing such engagement.

20 Another object of my invention is to provide means for severing a strip of paper into predetermined lengths, with means for feeding the severed or partially severed length, relatively faster than the feed of the strip 25 to insure separation of the length from the strip.

Another object of my invention is to provide a machine for severing a strip of paper into predetermined lengths, with means for 30 compiling the lengths, one above the other within a suitable compartment, or otherwise.

Another object of my invention is to provide a machine, whereby the record strip of an autographic register can be severed into 35 predetermined lengths, separating the individual sales records and compiling the same consecutively and within or upon a container.

Another object of my invention is to provide 40 a pair of paper feeding and cutter rolls positively rotated relatively to each other, with a toothed cutter fixed upon the periphery of one of said rolls, and a tension plate yieldingly mounted upon said roll adjacent 45 to the cutter blade, and a compression bar mounted upon the opposite companion roller, adapted to register with said cutter blade in the rotation of the rolls, for producing a transverse line of perforations through the 50 strip of paper for partially severing the strip.

The various other features of my invention

are more fully set forth in the description of the accompanying drawings, forming a part of this specification, in which:— 55

Figure 1 is a side elevation of my strip cutting machine. Fig. 2 is a top plan view thereof. Fig. 3 is a side elevation of the machine opposite that of Fig. 1. Fig. 4 is a section on line x, x , Fig. 2. Fig. 5 is a 60 section on line v, v , Fig. 4, and enlarged, of one of the feeding and cutting rolls. Fig. 6 is an enlarged central vertical section of the second cutting roll. Fig. 7 is a detail section on line z, z , Fig. 3. 65

This machine is primarily adapted for cutting a strip of paper into predetermined lengths, the strip representing the record strip of an autographic register, which is usually rewound from one roll into another, 70 and contains the records of sales and the like. Such record roll is inconvenient in making book entries or using the same as a reference, for the same must always be unwound when reference is desired to a particular record and then again rewound for filing. With my machine, these individual records are severed from the strip and sequentially compiled in their order of record 75 on the strip in substantially book form. 80 Thus, convenient access and ready reference can be had to each record.

It is obvious, that the principle of my invention can be applied directly within an autographic register, severing the record 85 lengths after each recording operation or entry in the use of the autographic register, instead of an independent machine, as herewith illustrated, without departing from any of the features of my invention. Further, while I have shown the same operated manually by a hand crank, it is obvious, 90 that any motive power may be employed or the same operated when used in conjunction with an autographic register by the manipulating means of the register, and, therefore, the broad principles of my invention relate to means for severing a strip of paper into a series of predetermined lengths and 95 compiling the same one above the other in 100 the order of severance.

In the drawings, 1 represents the side frames of the machine; 2 a pair of yielding roll supports or carriers mounted upon the

side frames 1, and between which the roll of paper 3 is mounted, the roll-supporting arms applying the proper tension to the roll requisite in feeding paper therefrom and common in autographic registers.

4 represents a guide plate which is secured between the side frames and over which the strip of paper is fed, so as to direct the paper between the combined feeding and severing rolls 5, 6.

5 represents the lower feeding and severing roll journaled in a fixed bearing between the side frames, the axle 7 thereof projecting through the bearings of the side frames 15 and upon one end of which a hand crank 8 is fixed. The upper roll 6 is provided with an axle 9, journaled in the slide-block 10, slidably mounted in a bearing bracket 11, formed on the side frames 1, see Figs. 1 20 and 3. The slide-blocks 10 in each of the brackets 11 are maintained under downward tension by a spring 12 mounted in each of the brackets to maintain the peripheries of rolls 5 and 6 under frictional engagement with each other for feeding the strip between the rolls. The cutters are provided with coacting cutter or perforating mechanism hereinafter described, which is relieved of any pulling strains through 30 the feed of the paper by reason of the combined results of the rolls in feeding and partially severing the strip of paper. This form of feed and mechanism for mounting a pair of coacting rolls is old and well-known in the art and commonly employed in autographic registers.

13 represents a pinion fixed upon the axle 7 of the lower roll in mesh with a pinion 14, fixed upon the axle 9 of the upper roll, 40 for positively rotating said rolls relatively to each other to insure a predetermined length of feed of the strip of paper. The upper roll 6 is provided with a toothed cutting blade 15, fixed within a slot formed in 45 said roll, with the toothed edge projecting beyond the periphery of the roll.

16 represents an ejector plate yieldingly mounted in a transverse slot formed in the periphery of the roll 6, telescopically engaging over the cutter blade 15, and yieldingly mounted on the roll by means of the lugs 17, or pins, projecting from the plate 16, and into an orifice formed in the roll, and 18 represents a spring engaging against each 50 of said pins for exerting upward pressure to the plate 16, to project the same beyond the periphery of the roll. This plate is held in position by means of the collars 19, telescoped upon each end of the roll, see Fig. 5. 60 Thus, as the plate 16 engages the periphery of the lower roll, it will be moved inward and automatically thrown outward by the tension of the springs 18, after the rolls have rotated beyond such plate engagement, the

plates serving to eject or discharge the strip 65 of paper from any engagement with the teeth of the cutter blade and thereby prevent any clogging of the machine at this point. The lower roll 5 is provided with a coacting tension plate 20, yieldingly 70 mounted in a transverse slot formed in the periphery of the lower roll, and adapted to register with the cutter blade in the revolution of the rolls, so as to prevent slippage 75 of the paper, as the teeth are forced through the paper as they are projected into the slot in the lower roll, within which the tension plate 20 is mounted. Upon each end of the tension plate 20, lugs 22 are provided adapted in the rotation of the roll 5, to engage 80 with the periphery of the upper roll, to recede said tension blade with the intermeshing of the cutter within said tension blade slot, so as to relieve the cutter of any strains 85 incident to such tension blade movement, while at the same time, the tension or engagement with the cutter is sufficiently maintained to prevent slippage of the paper and insure the proper cutting action. The tension plate 20 also prevents the paper 90 from becoming engaged or adhering to the periphery of the roller, which, if permitted, would readily clog the machine. Therefore, as illustrated, both the upper and lower rolls are provided with means for preventing the 95 paper adhering or engaging with the cutter blade or rolls and thereby insuring a proper feed. The cutter blade is preferably made of toothed form, so as to make a line of perforations through the paper, not a complete 100 severing cut, and afterward severing the strip by a drawing action. The life of such cutter is greatly extended and renders the operation of the machine at a higher rate of speed than it is possible to produce with a 105 straight cutting edge or shear cut.

23 represents a guide plate mounted between the side frames 1, and between the cutting rolls 5 and 6, and pull rolls 24 and 25 mounted within bearings formed in the side 110 frames 1. The lower pull roll 24 is journaled in fixed bearings, while the upper pull roll 25 is journaled in yielding bearings, with the peripheries of said rolls coactively 115 maintained under tension. The upper roll 115 is mounted substantially as the upper cutting and feeding roll 6.

26, 27, and 28, represent a train of intermediate gears in driving connection with gear 13, and with gear 28 in mesh with a 120 gear 29 fixed upon the axle or shaft of the lower roll 24. This gear is of smaller diameter than the gear 28, so as to increase the rotation of the rollers 24, 25, so as to cause a pulling action upon the partially severed 125 length of paper and separate the same therefrom. The paper as it passes between these rolls is fed at a greater rate of speed than

the feed between the cutting rolls, thereby necessarily parting the paper along the line of perforations made by the cutter blade 15.

30 represents a gear fixed to the axis of roll 24, in mesh with a gear 31, fixed to the axle of the upper roll 25, producing a relative positive rotation of said rolls to insure the proper length of feed for each revolution thereof.

10 32 represents a hinged guide plate, adapted to direct the paper between the rolls 24 and 25. Said hinged plate is preferably hinged at its ends toward the pull rolls, adapted to be swung in an upward vertical position, to enable the paper to be grasped by the operator, to properly adjust the same relatively to the cutting rolls to insure a severing of the lengths along a proper line. As shown, the cutting action is had on each 15 revolution of the cutting rolls and their diameter governs the length of the cut strip, but it is obvious, that a series of cutters may be provided, so as to produce a series of cutting actions upon each revolution of the rolls. To release the frictional engagement between the peripheries of the feeding and cutting rolls 5, 6, the following means are provided.

34 represents cam levers pivotally mounted upon the axle of the upper roll 6 provided with the cam surface 35, adapted to be swung upon the periphery of the lower roll 5, thereby raising the upper roll and permitting the paper to be freely inserted and 20 adjusted between said rolls. 36 represents a rod connecting said levers and forming hand hold means for manipulating the same. The cam surfaces of levers 34 are engaged upon the periphery of the lower roll 5 by swinging the engaging portions of the levers in a direction reverse to the feed of the paper for releasing the peripheral engagement of the rolls 5 and 6, and therefore, when the rolls are rotated in a direction to feed the 25 paper, the levers will be automatically released from roll engagement obviating the necessity of manual release or disturb the operation of the rollers.

In order to compile and bind the severed 30 lengths, the following instrumentalities are provided:—37, 38, represent guide rods to properly direct and support the paper until it is released from its feed by the pull rolls 24 and 25. 39 represents a swinging arm 35 preferably formed with a medial loop 40. This arm 39 is fixed to the rock shaft 41. 42 represents an arm fixed to the rock shaft 41, and 43 represents a rod pivotally connected to said arm 42 and guided in the 40 bracket 44, projecting from one of the side frames, the opposite end of said rod engaging with the cam 45, fixed to the main driving shaft 7. 46 represents a coil spring encircling said rod 43, one end engaging one

of the brackets 44, its opposite end engaging 65 a collar 47, fixed on the rod 43. This spring maintains the free end of the rod in contact with the periphery of the cam 45, whereby the rod 43 is reciprocated through the rotation of the cam 45, thereby swinging the 70 arm 39 upon each rotation of the main driving shaft 7. The arm in normal position is swung upward, permitting the paper to pass between it and the guide rods 37 and 38, and at the proper time swung downward to 75 deposit the cut length on the receptacle or container 49, detachably mounted between the side frames 1. This container may be in the form of a base plate provided with a vertically projected pin 50, upon which the 80 paper is forced by the loop 40, of the arm 39, thereby securing the cut lengths in a compiled condition.

The machine is destined to feed a web between severing mechanism to divide the 85 same into individual lengths, and advance each length to binder storage mechanism to sequentially compile and bind the same. The disclosure herein having special reference to record sales webs taken from or issuing from an autographic register comprising a strip of paper, noting a series of individual sales or the like entries, each made within a defined area in sequence of issuance recorded by manifolding processes 90 in an entry upon an original slip or sheet and the length of each severed record entry may be equal or coördinate with the relative length of the original sales slips issued from the autographic register. 100

The lengths after being severed from the continuous strip are serially advanced to a position to be engaged by the swinging arm 39 and sequentially compiled upon the binder pin 50, projecting from the storage 105 compartment or container 49. The storage binder mechanism may be of any conventional form other than the container and binder pin illustrated, having the utility of a loose sheet binder for either temporarily 110 or permanently securing the sheets or severed lengths together.

It is obvious, that by changing the outline of the cam 45, the reciprocation of the rod 43 can be relatively governed for producing a proper time movement of the arm 39, to sequentially compile the lengths relatively with the speed or number of cuts made upon each revolution of the cutting rolls 5 and 6. 120

Having described my invention, I claim:—

1. In a machine of the class described, a pair of coating rolls for feeding and partially severing a strip of paper into lengths, means progressive of said rolls for feeding the partially severed lengths relatively faster than the first-named rolls to sever

- the length from the strip, guiding means for guiding said strip interposed between said sets of rolls, a storage compartment for receiving said lengths, and binder means 5 within said compartment, and means operated in time movements relatively with the feed of the paper, to present the lengths to said binder means sequentially.
2. A pair of conjoint paper feeding and 10 cutting rolls pressed yieldingly together, a cutter blade on one of said rolls, adapted to partially sever the paper at predetermined intervals relative to the rotation, and peripheral surfaces of said rolls adapted to impinge upon and feed the paper, and means for rotating said rolls in unison.
3. In a machine of the class described, a 15 pair of coacting feeding and cutting rolls having their peripheries yieldingly engaging each other, coacting cutter elements on said rolls adapted to partially sever the paper at predetermined intervals relative to the rotation of the rolls, a second pair of coacting feeding rolls adapted to feed the 20 partially severed lengths of paper relatively faster than the feed of the first set of rolls to sever the lengths from the strip.
4. In a machine of the class described, a 25 pair of coacting feeding and cutting rolls, their peripheries yieldingly engaged, a serrated cutter blade axially mounted upon one of said rolls and projected beyond the periphery thereof, a cutter guard member telescopically engaged over the cutter blade and yieldingly mounted upon the roll, a member 30 yieldingly mounted upon the second roll adapted to aline and register with said cutter blade in the rotation of the rolls, and projections mounted upon said member adapted to engage said first-named roll to 35 depress said member.
5. In a machine of the class described, a 40 pair of coacting feeding and cutting rolls, one of said rolls yieldingly engaging the second, a cutter blade axially mounted upon one of said rolls and projected beyond the periphery thereof, a cutter guard member telescopically engaged over said cutter blade and yieldingly mounted, and adapted to be 45 depressed by the opposing roll, a member yieldingly mounted upon the second roll within a groove axially of the roll adapted to register with said cutter blade in the rotation of the roll and be depressed by engagement with the opposing roll in advance 50 of knife registration.
6. In a machine of the class described, a 55 pair of coacting feeding and cutting rolls having their peripheries yieldingly engaging each other, coacting cutter elements on said rolls adapted to partially sever the paper at predetermined intervals relative to the rotation of the rolls, a second pair of coacting feeding rolls adapted to feed the 60 partially severed lengths of paper relatively faster than the feed of the first set of rolls to sever the lengths from the strip, guiding means interposed between said sets of rolls for directing the strip from the first set to the second, and a storage compartment for receiving the lengths.
7. A pair of conjoint paper feeding and 65 cutting rolls pressed yieldingly together, a cutter blade on one of said rolls, adapted to partially sever the paper at predetermined intervals relative to the rotation, and peripheral surfaces of said rolls adapted to impinge upon and feed the paper, means for rotating said rolls in unison, lever mechanism for releasing the roll engagement, 70 means progressive of said rolls to sever and advance the paper lengths, a binder pin adapted to receive the advanced lengths, and a member movable to encompass the pin and press the paper thereon.
8. A pair of conjoint paper feeding and 75 cutting rolls pressed yieldingly together, a cutter blade on one of said rolls, adapted to partially sever the paper at predetermined intervals relative to the rotation, and peripheral surfaces of said rolls adapted to impinge upon and feed the paper, means for rotating said rolls in unison, lever mechanism pivotally mounted upon the axis of one of said rolls adapted to engage the second roll when swung in a direction reverse 80 to the feed of paper, to release the roll engagement, and adapted to be automatically released and bring the rolls into peripheral engagement through the rotation of the 85 rolls in a paper feeding direction.
9. A pair of conjoint paper feeding and 90 cutting rolls pressed yieldingly together, a cutter blade on one of said rolls, adapted to partially sever the paper at predetermined intervals, relative to the rotation and peripheral surfaces of said rolls adapted to impinge upon and feed the paper, and means for rotating said rolls in unison, a second pair of coacting rolls higher speeded to 95 sever and advance the lengths of paper, storage binder means adapted to receive an advancing length when discharged by said second set of rolls, and means operated in time movements relatively with the feed of 100 the paper for sequentially binding the lengths.
10. In a machine of the class described, a 105 pair of coacting rolls for feeding and partially severing, means progressive of said rolls for feeding the partially severed lengths relatively faster than the first-named rolls, to sever the lengths from the strip, storage binder means in advance of said second-named feeding means, and 110 means operated in time movements relative with the feed of the paper to present the lengths to said binder means sequentially.

11. In a machine of the class described, a pair of coacting rolls for feeding and partially severing a strip of paper into lengths, means progressive of said rolls for feeding the partially severed lengths relatively faster than the first-named rolls, to sever the lengths from the strip, binder storage means adapted to receive the advancing strip comprising a binder pin, a swinging arm adapted to straddle said pin and press the length through the pin and intermediate connections between said first-named feeding roll and arm, for swinging the arm in time movements relatively with the feed of the paper.

12. In a machine of the class described, coacting feeding and paper severing rolls adapted to feed and sever a strip of paper into lengths, binder means adapted to receive the advancing lengths sequentially, and means operated in time movements relatively with the feed of the paper for engaging the lengths through the binder means.

13. A device of the nature disclosed combining a plurality of rolls arranged progressively in coacting pairs rotated at different speeds, the lower speeded pair of rolls receiving the paper between them and advancing it to the higher speeded second pair of rolls and provided with coacting

paper mutilating elements to partially sever or score the paper at intervals, and the second pair of rolls increasing the advance of paper beyond the first pair of rolls, thereby completing the severance of the paper and rapidly serve the severed strip in advance of a subsequent strip severance and sequentially compile the strips.

14. A device of the nature disclosed, combining a plurality of rolls arranged progressively in coacting pairs rotated at different speeds, comprising a first or lower speeded pair of rolls receiving a strip of paper between them and advancing it to a higher speeded second pair of rolls and provided with means for scoring the paper at intervals, and a second pair of rolls increasing the advance of paper for severing said strip at its scored intervals in sheets and intermittently sequentially delivering the sheets for compilation, and a member interposed between said pairs of rolls for supporting and guiding the paper to said second pair of rolls.

In testimony whereof, I have hereunto set my hand.

ALBERT KRAUTH.
